ATTORNEY.

UNITED STATES PATENT OFFICE.

ANTHONY C. FOWLER, OF BROOKLYN, NEW YORK.

REVOLVING TABLE-TOP.

SPECIFICATION forming part of Letters Patent No. 271,054, dated January 23, 1883.

Application filed July 6, 1881. (No model.)

To all whom it may concern:

Be it known that I, ANTHONY C. FOWLER, of Brooklyn, in the county of Kings and State of New York, have invented certain new and useful Improvements in Revolving Table-Tops; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

This invention relates to improvements in self-waiting tables, and has for its object to provide a comparatively inexpensive table of this character, in which a yoke or bail handle is pivoted to the pivot-pin on which the rotary top piece of the table revolves, said handle being adapted to be turned down into a recess in the said top piece, flush with the upper side thereof, so as to present no projecting part.

This invention is illustrated in the accompanying drawings, in which Figure 1 represents a vertical cross-section. Fig. 2 is an inverted 25 plan view of the lower section or base. Fig. 3 is a detail view of the handle.

Similar letters of reference indicate corresponding parts.

The letter A designates the base-piece; B, the top piece; C, the pivot; D, the handle, and E the recess in the top piece for receiving the handle. Both the base-piece A and top piece, B, are preferably made of circular form, and the top piece is adapted to revolve upon 35 the base-piece by means of balls or rollers, running in grooves g, Fig. 2, formed in both pieces, one opposite to and coincident with the other. The top piece, B, is provided with a rim, B', to prevent dishes or other articles from falling off of it, the rim being formed by sinking the top piece within the rim, as shown, and, if desired, said top piece may be molded of paper-maché, so that it will rapidly absorb moisture. The pivot C extends through the top 40 piece, B, into the base-piece A, to which it is

secured by means of a screw-thread, and the pivot is provided with a washer or head, h, which is sunken into the top piece in a line with the handle-recess E. The handle D is yoke-shaped, and is arranged to swing on the pivot C at its upper end, while the recess E is formed on one side of the pivot, in the upper surface of the top piece, of suitable size to receive the handle when it is swung to a lower position.

It will be seen that the handle D is a medium for carrying the entire top from one place to another, while by extending the pivot C through the top piece into the base-piece and connecting the handle to such pivot both pieces 50 A B are practically sustained, the arrangement of the handle to swing into the recess E, moreover, leaving the top piece perfectly flat, which obviously facilitates transportation.

I am aware that it is not new, broadly, to 65 combine a revolving top piece with a stationary base-piece having balls for supporting the top piece; and I am also aware that it is common to arrange the handles of chests, drawers, &c., to swing into recesses, and I do not claim such 70 as my invention.

What I do claim, and desire to secure by Letters Patent, is—

In a self-waiting table, the combination of the grooved base-piece, the rotary grooved top 75 piece, provided at its center with the recess E, the balls arranged in the grooves of the said pieces, the pivot-pin C, attached to the base-piece, and having a fixed head resting in the recess of the rotary top piece, and a pivoted 80 handle adapted to turn into the recess in the top piece, substantially as and for the purpose described.

In testimony that I claim the foregoing I have hereunto set my hand this 3d day of July, 1881. 85

ANTHONY C. FOWLER.
